UNITED STATES PATENT OFFICE.

THEODORE SCHEFFLER, OF PATERSON, NEW JERSEY, ASSIGNOR OF ONE-HALF TO ROBERT ATHERTON, OF SAME PLACE.

POWER-TRANSMITTING DEVICE.

SPECIFICATION forming part of Letters Patent No. 448,575, dated March 17, 1891.

Application filed November 1, 1890. Serial No. 370,062. (No model.)

To all whom it may concern:

Be it known that I, THEODORE SCHEFFLER, a citizen of the United States, residing at Paterson, Passaic county, and State of New Jersey, have invented certain new and useful Improvements in Power-Transmitting Devices; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

This invention relates more especially to railway-cars operated by motors, hoisting-engines, and similar classes of machinery.

The object of the invention is to enable the power of a rapidly-revolving main driving-shaft to be transmitted to another shaft requiring reduced speed without the aid of gears or pulleys and without noise; to insure motion in the shaft having reduced speed in only the direction required, even if the motion of the main driving-shaft be reversed, and to provide a ready and reliable means for reversing the motion of the shaft having the reduced speed without the necessity of stopping the motion of the main driving-shaft.

The invention consists in the improved reversible clutches attached to a shaft revolving at less speed than the main shaft and the connections between said clutches and the main shaft.

It also consists in a system of lever-connections with the clutches, whereby the clutches can be readily and quickly reversed, and also in the combination and arrangement of the various parts, all of which will be hereinafter more fully described, and finally embodied in the clauses of the claim.

Referring to the accompanying drawings, in which like letters and numerals of reference indicate corresponding parts in each of the several figures, Figure 1 is a top plan view of one-half of a railway-car truck embodying my invention, showing the connections between the main driving-shaft and the clutches on the car-axles, and also the lever-connections for reversing the clutches. Fig. 2 is a side view of the connections between the main

shaft and the car-axles. Fig. 3 is an end view showing the reversing mechanism. Fig. 4 is a detail front view of a reversible clutch when arranged to turn in one direction, and Fig. 5 is a front view of the same clutch when arranged to turn in a direction opposite to that shown in Fig. 4. Fig. 6 is a section through line *x*, Fig. 4. Fig. 7 is a transverse vertical section through the clutch, and Fig. 8 is a section through line *y*, Fig. 4.

In said drawings, A represents a portion of a car-truck frame in which are arranged axles B B', carrying wheels B" B'" between the axles, and preferably midway between them is arranged on the truck a main driving or motor shaft C.

Upon one or both ends of the shaft C are arranged eccentrics or cranks D, with outwardly-extending crank-pins E. On the outer end of these pins is secured in any desirable manner a collar or stop F. Upon these crank-pins and inside the collar F are pivoted connecting-rods G G', and to the outer ends of these rods are pivoted, by means of pins I I', 70 crank-arms H H', rigidly secured to clutches K K', loose on the axles B B'. Lateral motion of these clutches is prevented by a pin or in any other desired manner, as shown in Figs. 4, 5, and 7.

On the axles B B' are firmly secured round-shouldered plates L L', provided with annular grooves a a, adapted to receive the two parts b b' of a metallic ring. These parts b b' are each made of such length that when placed in the recess a there shall be sufficient space to receive one end of a clutch pin or bar c, the other end of said pin or bar resting in a slot d in the outer periphery of the clutch K, as shown in Figs. 4 and 5. This slot d is 85 made wide enough to receive on each side of the pin or bar c sliding locking-pins e e', pivotally secured at one end to lever f, fulcrumed at f' to a stop g, firmly secured to or made integral with the clutch K, and so adjusted 90 and arranged that when the clutch pin or bar c is in the position shown in Figs. 4 and 5 longitudinal motion of the pin will be prevented by the stop g, as will be manifest. The inside end of the clutch is provided with an annular shoulder h, with a slot corresponding to slot d. The locking-pins e e' are made of

such length that when they are respectively moved forward by the lever *f*, as shown in Figs. 4 and 5, they will engage with the side of the clutch pin or bar *c* and prevent the 5 axle from turning forward when in the position shown in Fig. 4 or backward when in the position shown in Fig. 5.

Upon the under side of the floor of the car and extending longitudinally its entire length 10 is a rod 1, arranged to oscillate in bearings 2, secured to the floor 3, as shown in Fig. 3. To each end of the rod 1 is secured an operating-lever 4. To the shaft are secured, also, levers 5, arranged and adapted at their lower 15 ends to be pivoted to short levers 5', attached to sliding bars 6, provided with elongated slots 7 7, in which are adjusted pins 8 8, on which the bar 6 slides. These pins are secured to blocks or studs 9 on the end of the 20 truck-frame A.

The sliding bar 6 is constructed with arms 10 10, to the outer ends of which are pivoted connecting-rods 12 12, the other ends of said connecting-rods being pivotally connected to 25 the lever *f*.

I have shown in the drawings my improvement as applied to an electric car, the motor being attached to the shaft C and connections made therefrom to both wheel-axes; but when 30 desired connection can be made with only one wheel-axle; but the double connection is preferable, as there is more steadiness of motion and less liability to jerks than when only one wheel-axle is connected.

35 In hoisting-engines and similar machinery the connection is made from the main or driving shaft directly to the drum-shaft carrying the hoisting-rope.

By the arrangement of the reversible 40 clutches on the wheel-axle and their connections with the driving-shaft the wheel-axle can only be turned in the direction according to the situation of the locking-pins on the clutch, and a reversal of motion of the driving-shaft will not reverse the motion of the 45 wheel-axes, such reversal of the wheel-axes being only obtained by reversing the clutch by means of the sliding pins, as above described. This arrangement of reversible 50 clutches forms a perfect brake, as the car can be stopped very quickly, as by reversing the clutch when the car is in motion the wheel-axle will at once stop and the wheels will all slide on the track. When the car is going up 55 a grade, no backward motion can be had, even if the motor-power be stopped or disarranged.

The operation of the clutching mechanism is as follows: When the sliding pins are in the position shown in Fig. 5, the clutch-pin *c* 60 lies evenly on the sliding pin *e* and has a uniform bearing thereon, and as there is no binding or straining on the ring the plate L can freely turn on the ring in a forward direction only; but if the wheel is started backward 65 the sliding pin *e'* will catch on the outer

end of the clutch-pin, as shown in Fig. 5, and cant the clutch-pin *c*, causing it to bind the ring firmly to the side of the annular groove *a* and prevent any backward movements of the wheel-axle. When power is applied to 70 the main driving-shaft, it is transmitted to reversible clutches on a receiving-shaft by means of lever-connections and at a reduced rate of speed. The crank-arms secured to the loose clutches on the shaft should be so 75 arranged that when one crank-arm is moving its clutch to its extreme limit in one direction the other crank-arm is moving its clutch in the opposite direction.

Having thus described my invention, what 80 I claim as new, and desire to secure by Letters Patent, is—

1. An improved power-transmitting device, as herein described, consisting of a main driving-shaft, crank on said shaft, a receiving-shaft, a reversible segmental-ring friction-clutch on said receiving-shaft, a crank-arm secured to said clutch, and a rod connecting said crank-arm and the crank on the main shaft, all said parts being constructed and 85 adapted to operate as described, and for the purposes set forth.

2. In a power-transmitting device, a reversible segmental-ring friction-clutch on the receiving-shaft, a crank-arm secured to said 90 clutch, and means for connecting said crank-arm with the main driving-shaft, as described, and for the purposes set forth.

3. A reversible clutch, as herein described, consisting of a plate or disk provided with an 95 annular groove and adapted to be secured to a shaft, segmental portions of a ring fitting in said groove and forming less than a complete circle, a clutch pin or bar, one end of which is adapted to fit in said groove, a loose 100 clutch portion on said shaft provided with a bearing for the other end of said clutch bar or pin, a stop on said clutch portion holding said bar in position, a lever pivoted to said clutch portion, and sliding pins pivoted to 105 said lever and adapted to be reciprocated in opposite directions, all said parts being adapted to operate as described, and for the purposes set forth.

4. In a clutch, a reversible segmental-ring 110 mechanism consisting of a clutch-pin adapted to hold in position the segmental ring, alternately-sliding pins pivoted to a lever, and means for operating said lever from a distance, all said parts being arranged and adapted to 115 operate as described, and for the purposes set forth.

In testimony that I claim the foregoing I have hereunto set my hand this 25th day of October, 1890.

THEODORE SCHIEFFLER.
